W. H. ROWLEY,
ELECTRODE,
APPLICATION FILED DEC. 16, 1913.

1,156,315.

Patented Oct. 12, 1915.

UNITED STATES PATENT OFFICE.

WILLSON H. ROWLEY, OF UNIVERSITY, MISSOURI.

ELECTRODE.

1,156,315.

Specification of Letters Patent.

Patented Oct. 12, 1915.

Application filed December 16, 1913. Serial No. 806,998.

To all whom it may concern:

Be it known that I, WILLSON H. ROWLEY, a citizen of the United States, and resident of University city, St. Louis county, and

5 State of Missouri, have invented certain new and useful Improvements in Electrodes, of which the following is a specification containing a full, clear, and exact description, reference being had to the accompanying drawings, forming a part hereof.

10 My invention relates to improvements in electrodes or battery plates, and the object of my invention is to construct an electrode comprising metal lead fiber of minute and 15 ductile filaments, many of which are designed to have intimate contact with a supporting element, and the mass or body so arranged as to provide for permeation and circulation of the electrolyte and which arrangement of filaments and ductility provide for the growth of the filaments in the 20 oxidation or forming of the filaments.

25 A further object of my invention is to provide an electrode comprising bodies of metal lead fiber in the form of ductile filaments arranged to be supported on a grid with the filaments forming a porous veil, corrugated or roughened over the supporting grid, and many of the filaments designed to have intimate contact with the supporting element, whereby to obtain a maximum of filament length in a given length of supporting element and whereby the filaments having contact with the supporting element, will become active material. 30 And a further object of my invention is to construct an electrode of the composite type employing two forms of active material, one being metal lead filaments 35 and the other an oxide of lead, wherein the metal lead having the characteristics above noted serves as envelope for an oxid, which envelope hold or space apart the body of oxid from the surface of the supporting element in order to obviate zones upon the surface of the oxid body which will not offer permeation of the electrolyte, as distinguishable from such plates wherein the oxid is pasted or placed in immediate contact with the surfaces of the supporting element.

40 With the above purposes in view my invention consists in certain novel features of

construction and arrangement of parts as will be hereinafter more fully described, 55 pointed out in the claims and illustrated by the accompanying drawings, in which—

Figure 1 shows in elevation an electrode constructed according to my invention, the upper and right hand margins being completed, and portions of the lower and the left hand margins showing the ends of the filaments projecting beyond the margins of the grid, as before being united therewith; Fig. 2 is a plan of a strand or group of metal 60 lead filaments; Fig. 3 is an end elevation of one of the supporting elements showing the rib formation to produce channels to receive the strands of metal lead fiber; Fig. 4 is a longitudinal sectional elevation of one of 65 the frame members taken at right angles to Fig. 3; Fig. 5 is a view similar to Fig. 4 showing a strand of the metal lead fiber in place; Fig. 6 is a view similar to Fig. 5 showing a body of oxid applied to the strand 70 of metal lead fiber; Fig. 7 is a transverse sectional elevation of a composite plate taken on the line 7—7 of Fig. 1; and Fig. 8 is an enlarged fragmental longitudinal sectional elevation taken on the line 8—8 of 75 Fig. 1.

Referring by numerals to the accompanying drawings: 10 and 11 designate the frames of the electrodes which are preferably rectangular in shape and each provided 80 with a terminal such as 12.

Extending lengthwise of each frame are the parallel ribs or bars 13.

Between the points where the ribs 13 unite with the frames the frames are reduced in 85 thickness in order to form channels such as 14 extending the length of the frame members.

15 designates the grid bars which, as clearly shown in Fig. 4, are of less thickness 90 than the bars 13.

Each of the frames 10 and 11 carries a transverse bar 16.

17 designates strands of metal lead fiber which consist of continuous metal lead 100 filaments. The strands 17 are placed in each channel 14 of each frame and, as shown in Fig. 5, are shaped over the grid bars 15 with their ends projecting beyond the end members of the frames 10 and 11.

105 In this placing of the strands over the

grid bars care should be taken to avoid destruction of the porosity of the strand over the grid bar.

18 designates a body of oxid of lead which is pasted or placed upon the screen, veil or envelop consisting of strands 17.

It is obvious that one face of the body 18 of oxid will be corrugated or roughened and due to the porosity of the strands 17, 10 the oxid will possess a minutely divided surface in addition to the corrugated surface by reason of its entering into the innumerable interstices of the porous strands of metal lead fibers.

18 By reference to Figs. 7 and 8, it will be observed that the complete electrode comprises two frames having the screens of metal lead fiber and the bodies of oxid of lead possessing the characteristics just described, and placed between the two bodies 20 of lead oxid is a screen or veil 19 which is made up of metal lead fiber, the filaments of which extend continuously from one side to the other of each of the frames.

25 As shown in Fig. 1, the ends of the filaments entering into the screen 19 extend beyond the sides of the frames. The two frames carrying the screens and bodies of lead oxid as described, after being placed together, are subjected to heat or to the 30 flame of a burner which will unite the ends of the filaments entering into said screens, will unite the ends of the filaments with the frame members, and also unite the frame members at some point of said connecting frames.

The two frames are then further united 40 at the bars 16, either by rivets such as shown in Fig. 1, or by welding, which act 45 will bring into intimate contact with said bars the filaments of the strands 17 so that in the event there is a strand broken between its ends, said broken filament will have at least one point of intimate contact with the frame, so that when it is put into service it will not be isolated and will of itself become active material.

By reason of the multiple of minutely divided surfaces of the active material in the 50 form of oxid, it is obvious there is active material immediately available for service and, by reason of the particles of the minutely divided surface being in contact with metal lead filaments extending to and electrically connected with the supporting element, there will be an immediate and uninterrupted flow of energy from these minute particles of active material.

Due to the oxid bodies being enveloped in 60 porous veils or envelops of metal lead fiber, it is obvious that the electrolyte has access to the entire surface and body of the oxid, the porous veil serving to hold and space apart the oxid body from the grid bars of 65 the supporting frames in order to obviate

dead or inert zones upon the surface of the oxid body, as would be the case if the oxid body were pasted or placed in immediate contact with said grid bars.

While I have shown and described a composite electrode having two forms of active material, the oxid and the metal lead fiber, I do not wish to be understood as limiting myself to this arrangement for it is obvious that a highly efficient electrode may be constructed with the metal lead fiber alone as active material.

It is to be observed that I have arranged with great care for immediate contact between each individual filament of the metal 80 lead fiber and the supporting frame in order to avoid isolated filaments which, of course, would be functionless.

An important characteristic of my improved electrode lies in the relative arrangement of the individual filaments to avoid density or compactness of the body of filaments in order to provide for the growth of the filaments in forming, oxidizing or sulphating, so that the body of filaments may 90 in itself provide and compensate for said growth rather than to impart strains incident to such growth to the supporting frames, thus such an electrode will not buckle or be distorted.

A further characteristic of my electrode of the composite type lies in the employment of a porous envelop constructed of metal lead fiber possessing a sufficient body to prevent "shedding" of the oxid.

I claim:

1. An electrode, comprising a frame in the form of a grid, a body of active material in the form of fiber, the individual filaments of which are united with said frame and between their ends shaped over said grid to produce an uneven surface.

2. An electrode, comprising a frame in the form of a grid, a body of active material in the form of fiber, the individual filaments of which are united with said frame and between their ends shaped over said grid to produce an uneven surface, and a body of active material comprising an oxid of lead applied to said uneven surface.

3. In an electrode, a pair of frames comprising grids, a screen of metal lead fiber, the filaments of which are united with said frames and shaped over said grids to produce uneven surfaces, and a body of active 120 material comprising an oxid of lead enveloped between said uneven surfaces.

4. In an electrode, a pair of frames comprising grids, screens of metal lead fiber, the filaments of which are united with said frames and their bodies shaped over said grids to present uneven surfaces, bodies of active material comprising an oxid of lead supported by said screens, and a screen of metal lead fiber interposed between said 120

oxid bodies, the filaments of which last mentioned screen are united with said frames.

5. In an electrode, a grid-like frame, a body of active material in the form of a porous veil of metal lead filaments secured to said frame and covering the grids thereof, and a body of active material comprising an oxid of lead supported by said veil and held separated from the grids of the 10 frame by said veil.

6. In an electrode, a frame, a porous envelop comprising loosely assembled metal lead filaments, each of which is designed to be united with said frame, and a body comprising an oxid of lead within said envelop and held separated thereby from the frame.

7. In an electrode, a pair of connected frames, a porous body comprising loosely assembled metal lead filaments supported by each frame, each of which filaments is designed to be united with one or the other of

said frames, and a body comprising an oxid of lead enveloped by said filaments and held separated from the frames thereby.

8. In an electrode, a pair of grid-like frames, a porous veil of metal lead filaments having their ends secured to said frames and their body portions between the ends loosely assembled and covering said grids, and bodies comprising an oxid of lead applied to said porous veils and separated from the grids of the frames by said veils, said frames holding said bodies of oxid being united.

In testimony whereof, I have signed my name to this specification, in presence of two subscribing witnesses.

WILLSON H. ROWLEY.

Witnesses:

EDWARD E. LONGAN,
E. L. WALLACE.
